CLAIM

The ornamental design for a combined vacuum breaker for a bidet and mounting bracket, as shown and described.

DESCRIPTION

FIG. 1 is a right side elevational view of a combined vacuum breaker for a bidet and mounting bracket showing my new design, the left side being a mirror image of the right side;

FIG. 2 is a rear elevational view thereof;

FIG. 3 is a front elevational view thereof;

FIG. 4 is a top plan view thereof; and,

FIG. 5 is a bottom plan view thereof.
